UNITED STATES PATENT OFFICE.

JOHN A. BRILL AND GEORGE M. BRILL, OF PHILADELPHIA, PENNSYLVANIA.

CAR-TRUCK.

SPECIFICATION forming part of Letters Patent No. 430,418, dated June 17, 1890.

Application filed October 2, 1888. Serial No. 286,957. (No model.)

To all whom it may concern:

Be it known that we, JOHN A. BRILL and GEORGE MARTIN BRILL, citizens of the United States, residing at Philadelphia, in the county 5 Philadelphia and State of Pennsylvania, have invented certain new and useful Improvements in Railway-Car Trucks, of which the following is a specification.

Our invention has relation to that form of 10 trucks for street-railway cars which are independent of the car-body and attached thereto, so as to be removable therefrom, as fully set forth and claimed in another pending application filed June 25, 1888, Serial No. 278,160, 15 which trucks we denominate "independent rigid trucks" in contradistinction to the pivoted or movable trucks used for railway-cars.

Our present invention has for its primary 20 object to adapt to the independent rigid truck the "post" form of support or pedestal for the car-axle boxes, and to provide an improved spring-support for the frame suspended from the car-axle boxes; and, further, to secure the sand-boxes to the truck and provide them with actuating devices operated 25 from the platform or body of the car. Our invention accordingly consists of the combinations, constructions, and arrangements of parts as hereinafter described in the specification, and pointed out in the claims.

Reference being had to the accompanying drawings, Figure 1 is an elevation of the independent rigid truck with axle-box frame, electric motor, brake mechanism, axle-box 30 posts, and connections therefor, embodying our improvements, said truck being shown as detached from the car or its framing and without the sand-boxes to better show the axle-box posts and their connections. Fig. 2 is an 35 elevation of part of same, partly sectional, drawn to an enlarged scale. Fig. 3 is a like view showing the sand-boxes located on the axle-box frame. Fig. 4 is an elevation showing the truck attached to the bottom or frame 40 of the car with sand-box on the axle-box frame, braces or supports between the truck-frame and the lower chords or pedestal connecting-bars, and removable braces between said pedestal connecting-bars and the ends of the car, 45 the same being specially adapted for summer or other cars of long length, and Fig. 5 is an 50

elevation of the axle-boxes, showing usual form of equalizing-bar for use therewith.

A represents the independent rigid truck-frame, which consists, essentially, of a top-frame B, composed of two longitudinal sides b b, and end and intermediate cross-bars b' b'', respectively, of wood or metal, of any suitable configuration in cross-section; but we prefer to make it of flat bar-iron, the parts of 60 which are forged together to make when complete a frame B in one piece.

C C represent the axle-box post form of pedestals, consisting of top plates or castings c, posts c³, and bottom connecting bars or 65 yokes c⁵. The top plates c are grooved in their upper sides to form edge flanges c' for embracing the sides b of the top frame B, as more plainly shown in Fig. 2, and have near each end unthreaded or smooth openings c² 70 for the posts c³. The upper ends of the posts c³ are reduced in size to form shoulders c⁴, which reduced ends are threaded, as shown, and are screwed into threaded openings in the sides b b of frame B. The shoulders of 75 said posts c³ abut against the lower sides of the frame B, and the adjacent smooth parts of the posts pass through the openings c² in the plates c³ to maintain the top plates in position and to strengthen the screw-connection 80 of the posts with the frame B. If desired, however, the upper ends of posts c³ may be provided with nuts, as indicated at y, Fig. 2. Surrounding the posts c³ are spiral or other springs D, and between the top caps or plates 85 d for the springs and plates c are rubber or other elastic washers d', and corresponding washers d² are located between the bottom caps or plates d³ for the springs D and the spring-seats f on the axle-boxes. 90

The axle-boxes F may be of any suitable construction and the seats f project from the sides of the boxes in the usual manner and have openings therein for the passage of the posts c³, the lower ends of which are connected by bars c⁵, which may be straight or bowed, as shown, in order to pass below the axle-boxes. Between the axle-box spring-seats f and bars c⁵ and surrounding posts c³ are rubber or other elastic washers f'. The 95 ends of the bars c⁵ are connected by braces f² to the sides b of the truck-frame B to give 100

the required supports or bracing and strength to the lower ends of the posts c^3 , which ends are provided, if desired, with screw-nuts c^6 , located below the yokes c^5 . The axle-box 5 spring-seats f , between the boxes F and the posts c^3 , have bolt-openings f^{20} , surrounding which are seats or cups f^3 for rubber or other springs f^4 , furnished with top plates or caps f^5 , and through said caps, springs, and openings pass bolts f^6 , which secure depending brackets or yokes G to the lower side of the seats f , suitable elastic cushions f^7 being inserted between the yokes G and seats f . (See more plainly Fig. 2.)

15 The yokes G are located below the axle-boxes and are bifurcated vertically or grooved on their under sides to admit of the passage through their grooves of the yokes or bars c^5 . To yokes G is secured in any suitable manner the frame H, which connects all the yokes or axle-boxes together, and upon it are mounted, either wholly or partially, the electric or other motors I, also the track-brushes K, and, if desired, any suitable form of track-brakes. The sand-boxes L are shown secured to or mounted on the axle-box frame H, but if desired they may be located on the truck-frame B in any suitable manner. The sand-boxes have a suitable outlet-pipe l , with valve 25 or cut-off l' , which has a connection l^2 leading to a platform of the car, by means of which the valve is opened to drop sand upon the track-rails when desired. (See more plainly in Figs. 3 and 4.) By disconnecting the actuating cord or chain l^3 the sand-boxes 35 remain undisturbed on the truck when it is removed from the car.

40 The brake-shoe beams are mounted upon the frame B, and their actuating mechanism may be constructed and arranged for operation as desired; but we prefer to so construct and arrange the same as shown, and as fully described and claimed in still another application filed the 2d day of October, 1888, Serial No. 286,940, so that the brake mechanism remains upon the truck and admits of the latter being readily disconnected from the car-body, as fully set forth in said last-named application. For summer or long 45 lengths of cars we prefer to use the usual braces N, connecting the ends of the car to the outer ends of the bars c^5 , the connection between the bars c^5 and the braces N being made by means of a bolt-connection n , passing through a lug or lugs n' on the bars c^5 , and an end or block n^2 screwed to the adjacent end of the braces N so as to connect said brace-block or end n^2 and bar-lugs together to admit of readily disconnecting the braces N 50 from the bars c^5 when the truck is to be detached from the car-body. If desired, however, the form of coupling between braces N and bars c^5 , described and shown in another pending application of even date herewith, Serial No. 286,958, may be used.

55 To afford requisite strength for the sides b of frame B at or near the transverse middle

of the same, V or other suitably shaped brace- 60 rods P and pillars or posts p are bolted or secured to the connecting-bars c^5 , in which case the bars c^5 are joined together to form a lower cord for frame B, as plainly indicated in Fig. 4. So too, if desired, the usual form of equalizing-bar T, having spring-supports t on the axle-boxes, may be used in connection 75 with or without the springs D, and these bars T may be located and arranged as desired.

80 As the novel features of our improvements may be greatly varied within the spirit of invention, we do not restrict ourselves to the same as shown and described.

What we claim is—

1. The truck A, having axle-box frame H, sand-boxes L, with outlet-pipes on said frame, and devices leading to the car for opening 85 and closing said boxes, substantially as set forth.

2. In a car, the combination, with the car- 90 axle boxes, of a frame-spring supported on said axle-boxes, and sand-boxes on frame having actuating mechanism leading to the car, substantially as set forth.

3. The truck-frame A, composed of top side bars B, flanged plates c, axle-box posts c^3 , having collars or shoulders adjacent to and larger 95 than their upper ends, bars c^5 for connecting the lower ends of said posts c^3 , and braces f^2 , connecting bars c^5 to the bars B, substantially as set forth.

4. The independent rigid truck A, having 100 axle-box posts c^3 , top plates c, bars c^5 for the lower ends of said posts, and braces f^2 , substantially as set forth.

5. The independent rigid truck A, having frame B, groove-plates c, embracing the sides 105 of said frame, the posts c^3 , having shoulders near their upper ends, which ends pass through said plates and are secured to frame B, the axle-boxes F, having spring-seats f, bars c^5 , connecting the lower ends of posts c^3 , and braces 110 f^2 between said bars c^5 and frame B, substantially as set forth.

6. The combination of axle-boxes F, having spring-seats f for the car-springs D, spring-supports on said seats f between said springs 115 D and the boxes F, and a frame H, secured to said supports, substantially as set forth.

7. The combination of axle-boxes F, having spring-seats for springs D, the spring-supported bolts f^{20} between said boxes and springs D, yokes G, secured to said bolts, and frame H, attached to said yokes, substantially as set forth.

8. The combination of axle-boxes F, having spring-seats f, bolts f^{20} , caps f^5 on said bolts, 125 springs f^4 between said caps and seats f, yokes G, supported on said bolts, cushions f^7 between said yokes and seats f, and frame H on said yokes, substantially as set forth.

9. The combination of axle-boxes F, having 130 spring-seats f, posts c^3 , bolts f^{20} , caps f^5 on said bolts, springs between said caps f^5 and seats f, grooved yokes G, mounted on said bolts f^{20} , yokes or bars c^5 , connecting the lower

ends of said posts c^3 and passing through the grooves in said yokes G, and a frame H, mounted on the yokes G, substantially as set forth.

5 10. In combination with side bars of frame B, the flanged plates c, having smooth openings near each end, posts c^3 , having screw-threaded shouldered upper ends passing through said plate-openings and engaging 10 with threaded openings in the side bars of frame B, and connecting-bars c^5 for the lower ends of said posts c^3 , substantially as set forth.

11. The combination of axle-boxes F, having spring-seats f, posts c^3 , plates c, springs 15 D on said posts, caps d and springs d' between plates C and the upper ends of springs D, caps d^3 and springs d^2 between seats f and the lower ends of springs D, removable bars

c^5 for posts c^3 , and springs f' between the bars c^5 and seats f, substantially as set forth. 20

12. The combination of a car-body, a truck having an upper frame rigidly secured to the car-body, axle-box posts c^3 , secured to the upper frame, bars c^5 , connecting the lower ends of posts c^3 , and braces f^2 , connecting the upper frame and bars c^5 , and the braces N, coupled at one end to bars c^5 and at the other to the car-body, substantially as described. 25

In testimony whereof we affix our signatures in presence of two witnesses.
